Primary Examiner — Brian N. Vinson

(74) *Attorney, Agent, or Firm* — Morriss O'Bryant Compagni, Cannon, PLLC

(57) **CLAIM**

The ornamental design for the light and track assembly, as shown and described.

DESCRIPTION

FIG. 1 is a perspective top side view of the light and track assembly of the present invention.

FIG. 2 is a top side view of the light and track assembly.

FIG. 3 is a first end view of the light and track assembly.

FIG. 3A is an enlarged first end view of the light and track assembly.

FIG. 4 is a second end view of the light and track assembly.

FIG. 4A is an enlarged first end view of the light and track assembly.

FIG. 5 is a right side view of the light and track assembly.

FIG. 6 is a left side view of the light and track assembly; and,

FIG. 7 is a bottom side view of the light and track assembly.

1 Claim, 5 Drawing Sheets
